C. H. McCormick
Mower.

No. 2654
33,658

Patented Nov. 5, 1861

UNITED STATES PATENT OFFICE.

CYRUS H. McCORMICK, OF CHICAGO, ILLINOIS.

IMPROVEMENT IN REAPING AND MOWING MACHINES.

Specification forming part of Letters Patent No. 33,658, dated November 5, 1861.

To all whom it may concern:

Be it known that I, CYRUS H. McCORMICK, of Chicago, in the county of Cook and State of Illinois, have invented certain new and useful Improvements in Machines for Reaping and Mowing, of which the following is a full, clear, and exact description, reference being had to the accompanying drawing, which makes part of this specification, and which represents a view in perspective of a McCormick mower embracing my improvements.

My improvement consists in combining a driver's seat, a leaning-bar, and a jointed tongue in a machine whose weight is mainly balanced or poised both sidewise and lengthwise upon the main driving-wheel, so that the driver by shifting his position may incline the machine either forward or backward, or to the right or left upon the driving-wheel, which of course must be the center, or thereabout, of the weight of the whole machine.

The gearing-frame A is of triangular form, and is hung upon the axle d of the driving-wheel D, which is placed within this frame. This frame likewise carries the gearing.

The tongue C, by which the machine is drawn, is hinged by a joint-pin, e, to the front of the gearing-frame, so as to allow the frame to oscillate freely upon the axle of the driving-wheel.

The finger-beam B is attached to the rear of the frame A, and projects laterally beyond the frame a distance equal to the width of swath the machine is designed to cut.

The gearing is placed on the side of the driving-wheel opposite to that on which the finger-beam projects, and nearly counterbalances the weight of the cutting apparatus, so as to leave barely enough preponderance of weight on the side of the cutter to keep it running upon the ground when the machine is left free to assume its own position.

A seat for the driver is placed upon the frame, and extends across the driving-wheel, and is fitted on one or both sides with a leaning-bar, E, extending forward and inclining outward for the driver to bear against toward either side of the wheel, and thus determine a preponderance of weight on either side at will, or ceasing to bear against the leaning-bar and

sitting over the center of the wheel, leave the preponderance unaffected by his weight. The driver may likewise from his seat reach his foot forward, place it upon or near the rear end of the tongue, and, leaning forward with his body, throw his weight forward, causing the front of the machine to descend from the preponderance of weight in front of the axle of the driving-wheel. Then by again drawing back his foot and his body and resting upon the seat and leaning backward the driver will determine the preponderance of weight in rear of the axle, and the front of the machine will rise again and the rear descend.

It is obvious that the driver by moving simultaneously forward and laterally can turn the machine both forward and to either side. Hence he can raise the rear of the frame and the end of the finger-beam attached to it by leaning forward, and by moving sidewise at the same time he can raise the opposite end of the finger-beam, which but for this lateral change of the preponderance of weight would have drooped and remained resting upon the ground. This arrangement of parts in a compact machine necessarily involves the placing of the driving-wheel so that it will run as near to the standing grass as possible, in order to throw sufficient weight on its opposite side to counterbalance the weight of the cutters enough to allow of their being raised by so small a change in the distribution of weight as the leaning of the driver forward or backward, or outward against the leaning-bar E, or toward the opposite side of his seat. The power which is by this arrangement given to the driver to control the machine enables him, while cutting the grass comparatively clean, readily to avoid bringing the cutter into contact with many obstacles that would either damage it or stop the machine, but which could not well be avoided by machines of this class as heretofore constructed without driving so wide of the obstacles as to leave a large amount of grass uncut in patches, known as "balks."

What I claim as my invention, and desire to secure by Letters Patent, is—

The combination, in a mowing-machine balanced, or nearly so, upon its main driving-

wheel, of a driver's seat arranged over the driving-wheel, a leaning bar or bars on the side or sides of the driver's seat, and a jointed tongue so arranged that by a forward and lateral movement or a backward and lateral movement of his body the driver can correspondingly turn the machine upon the driving-wheel as a fulcrum, substantially as described.

In testimony whereof I have hereunto subscribed my name.

C. H. McCORMICK.
